UNITED STATES PATENT OFFICE.

FREDERICK B. WALTER, OF CHICAGO, ILLINOIS

HAIR-CUTTING INSTRUMENT.

942,298.

Specification of Letters Patent.

Patented Dec. 7, 1909.

Application filed January 31, 1908. Serial No. 413,653.

To all whom it may concern:

Be it known that I, FREDERICK B. WALTER, a citizen of the United States, residing at Chicago, in the county of Cook and State 5 of Illinois, have invented certain new and useful Improvements in Hair-Cutting Instruments; and I do hereby declare the following to be a full, clear, and exact description of the invention, such as will enable others skilled in the art to which it 10 appertains to make and use the same.

This invention relates to hair cutting instruments and has for its object the provision of an instrument of such character that 15 by its use, the use of scissors and hair clippers may be avoided, the instrument being so constructed and of such character that the hair cutting operation may be performed in much less time and in a more satisfactory 20 manner than is possible in the use of scissors and clippers.

The instrument is, in effect, a hair razor. Broadly stated, the instrument comprises a flat body provided along its lengthwise 25 edges with teeth and a blade supported upon the body in such a manner as to be adjustable to and from the body, the blade having two cutting edges each of which is parallel with respect to the point of one set of teeth. 30 By providing for this adjustment, the instrument may be adapted to cut a person's hair to any desired length and it is in this feature that the principal novelty lies.

In the accompanying drawings, Figure 1 35 is a plan view of the instrument, Fig. 2 is an edge view, and, Fig. 3 is a transverse section. Fig. 4 is a detail view showing the blade adjusted to lie in spaced relation to the comb.

As shown in the drawings, the instrument 40 comprises a flat body which may be formed of metal, hard rubber, celluloid, bone or any other suitable material from which combs are usually made and comprises a handle 5 and a working portion 6 along the longitudinal edges of which are formed series of 45 teeth 7. A threaded stud 8 is located midway of the working portion 6 of the body and this stud, when the body is made of 50 metal, is preferably formed integral therewith and when the body is made of other material, is set or fixed into the same. The stud mentioned above projects at right an-

gles from the working portion of the body and a blade 9 is formed with a central 55 threaded aperture 10 and is engaged upon the stud and prior to use of the instrument is rotated until brought to the proper distance from the said working portion of the body of the instrument and with its cutting edges 11 in parallel relation to the points of the teeth 7 after which a thumb jam nut 12 which is also engaged upon the stud, is screwed down upon the blade and holds it in adjusted position.

From the foregoing description of my invention it will be seen that I have provided an instrument for the purpose stated which may be more advantageously used than similar instruments now employed and 70 that the adjustability of the blade with respect to the working portion of the body of the device, permits of the user cutting a person's hair to the proper length. It will further be understood that the instrument 75 may be used in either hand and that instead of the upstrokes necessary with scissors and clippers, a downward stroke is all that is required in the use of my instrument embodied in my invention.

What is claimed, is:—

1. An instrument of the class described comprising a body provided with teeth, a stud formed upon the body, a blade, means whereby the blade may assume different positions upon the stud to and from the body with its cutting edge normally parallel with respect to the points of the teeth, and other means to hold said blade in adjusted position on the stud.

2. An instrument of the class described comprising a body provided with teeth, a threaded stud formed upon the body, a blade provided with a threaded aperture engaged upon the stud, said blade being adjustable to or from the body by rotation upon the stud, and a lock nut held upon said stud to secure said blade in adjusted position thereon.

In testimony whereof, I affix my signature, in presence of two witnesses.

FREDERICK B. WALTER.
